DES. 2138

Charles A. Shaw and James R. Clark, of Biddeford, Me.

Letters Patent No. 2138-Dated July 18-1865,

Design for a Sewing Machine.

The schedule referred to in these Letters Patent and making part of the same.

To all whom it may concern;

Be it known that we, Charles A. Shaw, and James R. Clark, of the City of Biddeford, in the County of York, and State of Maine, have invented or produced a new and original design for a Sewing Machine; and we do hereby declare that the following is a full and exact description of the same, reference being had to the accompanying drawings in which A is the ornamental fluted standard or upright, B the ornamental arm, C the ornamental bed-piece, having the ornamental needle-plate c. and fringe a. b; and D the ornamental base. The standard A, in itself considered, is not of our invention or production, and we do not claim the same when not combined with some part of the machine which is of our . . . production; but, in what we claim as of our production or invention and desire to secure by Letters Patent is The design for a Sewing Machine, shown and described.
